CLARKE W. STEWART, OF OLEAN, NEW YORK.

PUMPING MEANS FOR VACUUM-CLEANERS.

1,073,539.

Specification of Letters Patent. Patented Sept. 16, 1913.

Application filed September 19, 1912. Serial No. 721,163.

To all whom it may concern:

Be it known that I, CLARKE W. STEWART, a citizen of the United States, and a resident of Olean, in the county of Cattaraugus and 5 State of New York, have invented a new and Improved Pumping Means for Vacuum-Cleaners, of which the following is a full, clear, and exact description.

My invention relates to vacuum cleaners 10 adapted for the attachment of a hose carrying any approved form of suction nozzle, and the object of my invention is to provide an improved apparatus of very simple construction, and in which a bodily rocking 15 movement of the frame provided with a handle, will cause a system of bellows to produce the desired suction at the nozzle.

The distinguishing features of my invention, and the important structural elements 20 characterizing the preferred embodiment which is illustrated as an example, will be more particularly explained in the specific description hereinafter to be given.

Reference is to be had to the accompanying 25 drawings forming a part of this specification, in which similar characters of reference indicate corresponding parts in all the views.

Figure 1 is a front elevation of a vacuum 30 cleaner embodying my invention; Fig. 2 is a fragmentary side elevation; and Fig. 3 is a transverse vertical section taken on about the line 3—3 of Fig. 1.

In constructing a vacuum cleaner in accordance with the particular example given 35 as one practical embodiment of my invention, two side frames are provided, having supporting rockers 10, adapted to rest on the floor and desirably having rubber tires 40 10^a to increase the friction and give the rockers a better holding action on the floor. Each rocker is provided with a horizontal top bar 11 extending between the ends of the rocker, and with diagonal braces 12, rigidly fastened as at 12^a to the top bar 11, and at 12^b to the rocker 10, the said braces converging toward the top and the overlapped upper ends of which are received on trunnions 13, provided at the sides of an elongated head or block 14. On the trunnions 50 also is the bail 15 of a handle 16 by which the apparatus is manipulated, and rigid with the handle is a central partition 17 of a double-acting bellows, the handle and the 55 said diaphragm being movable relatively to the frame braces 12 and relatively to the

outer walls 18 of the bellows. For giving strength to the connection between the bail 15 and the central partition 17, I prefer to provide triangular members 17^a, at each side 60 of the said partition, and these may be integral with the ends of the bail 15 and receive fastening screws 17^b that take into the ends of the head 14. The material forming the bellows folds 19 extends at the sides and 65 bottom of the bellows from one outside wall 18 to the other. Each outer wall 18 is rigidly secured as at 21, to the adjacent diagonal brace 12 of the rocker frames, and near the bottom as at 22, are secured to the 70 top bars 11 of the rocker frames, so that the said walls are rigid with the rocker frames. The upper ends of the outer walls 18 are flexibly united as at 20 to the head 14, and there is a sufficient fullness of material at the 75 connection 20 to permit of a slight movement of the said head relatively to the said walls.

Mounted on the head 14 is a dust box, the cover 23 of which has an inlet nipple 25, or 80 its equivalent, for the connection of a hose 24, which in practice will be provided with any approved suction nozzle (not shown). The cover 23 is removable and is provided with a lateral bottom flange 26 that rests on 85 flanges 27 on the sides of the head 14. The dust box 28 over which the cover 23 fits is provided with a dust screen 29, and on the interior of the box 28, below the screen 29, is an interior rib 30, that rests on an interior 90 flange 31 on the head 14, the lower end of the box 28 thus being disposed outside of the flange 31. The construction is such that the cover 23 may be lifted and the dust box 95 then removed from the head 14, for dumping the collected dust. Communication between the dust box and the bellows is established by air ports 32 extending vertically through the head 14, said ports being commanded at the bottom by air inlet valves 33. 100 Suitable air egress valves 34 are provided in each wall 18 of the bellows.

With the described construction a reciprocating movement of the handle 16 will cause a rocking movement of the rocker frames, 105 and as the central partition 17 is in fixed relation to the handle, the partition and walls will assume the positions indicated by dotted lines at the left of Fig. 3, the left bellows will close and the bellows at the 110 right will expand. Upon a rocking of the apparatus to the right, the right hand bel-

lows will close and the left hand bellows will expand. Upon the expansion of a bellows the valve 34 will close and the inlet valve 33 of the bellows will open, thus producing 5 a suction within the dust box and in the hose 24. By thus moving the handle back and forth and rocking the frame, the dust will be drawn through the nozzle into the dust box, and collected in the latter.

10 It will be seen therefore that my invention provides an efficient cleaner, the cost of which will make it available for small homes and for people of moderate incomes; that it can be easily operated with little effort on 15 the part of the operator; that its operation will be essentially noiseless, and that the rubber-tired rockers will not only prevent slipping upon smooth floors when in operation, but they will prevent the marring of 20 furniture and polished floors, and when used on carpets will result in no injury to the latter. Furthermore, it is apparent that the apparatus may easily be carried from place to place, and that the arrangement of the 25 removable dust box at the top of the apparatus enables the operator to remove the dirt with convenience. Obviously, the motion may be imparted to the machine with one hand while the operator manipulates the 30 hose and nozzle with the other hand.

Having thus described my invention, I claim as new and desire to secure by Letters Patent,—

1. In a vacuum cleaning apparatus, the 35 combination of a rocker frame structure adapted to rest on a floor and to be rocked thereon, a bellows supported on said frame structure, a suction chamber in communication with the bellows, and means for operating the bellows by a rocking movement of 40 said frame structure, to produce suction in the said suction chamber.

2. In a vacuum cleaning apparatus, the 45 combination of a frame structure provided with rockers adapted to rest on a floor, a bellows, a suction chamber in communication with the bellows, one wall of which bellows is secured fixedly to said frame, a second 50 wall of the bellows being movable relatively to the first wall, and a handle adapted to rock the frame and cause a movement of one wall relatively to the other.

3. In a vacuum cleaner, the combination 55 of a frame structure mounted on rockers, a suction chamber at the top of the frame structure and relatively to which the said structure may rock, a bellows below the suction chamber, said bellows comprising a fixed and a movable wall and being in communication with the suction chamber, and 60 a handle for rocking the frame and moving one of said walls toward and from the other.

4. In a vacuum cleaner, the combination of a supporting frame structure mounted on rockers adapted to rest on a floor and to rock 65 thereon, a head supported at the top of the frame, a suction chamber supported on said head, a double-acting bellows comprising fixed walls and a rocking wall or partition between said fixed walls, and a handle in 70 fixed relation to the rocking wall and adapted to rock the supporting frame structure, the said head having air inlet ports establishing communication between the suction chamber and bellows at the sides of the 75 rockable wall, and the fixed walls being provided with air egress valves.

5. In a vacuum cleaner, the combination of a frame structure provided with rockers adapted to rest on a floor and to rock thereon, 80 a suction chamber, means for producing suction in the suction chamber by the rocking of the frame, and means for rocking said frame.

6. In a vacuum cleaner, the combination 85 of a supporting frame structure provided with rockers adapted to rest on a floor and to rock thereon, a head supported on the frame at the upper end and relatively to which the frame may rock, a suction chamber supported on the top of said head, means for rocking the frame, and means for producing suction in the suction chamber by the rocking of the frame.

7. In a vacuum cleaner, the combination 95 of a frame structure provided with rockers adapted to rest on a floor and to rock thereon, a head supported at the upper end of the frame, and relative to which the frame may have rocking movement, said head having 100 an air port extending from top to bottom thereof, a suction chamber removably supported on said head, at the upper side thereof, and means below the head and communicating with the air port thereof to produce 105 suction through the removable suction chamber, and the said air port, by the rocking of the frame.

8. In a vacuum cleaner, the combination 110 of a frame mounted on rockers adapted to rest on a floor to roll forward and back bodily, a suction chamber, a bellows communicating with the suction chamber, a device to cause rocking of the frame on its rockers, and means to alternately collapse 115 and distend the bellows by the back and forth rolling of the frame on its rockers.

In testimony whereof I have signed my name to this specification in the presence of two subscribing witnesses.
